UNITED STATES PATENT OFFICE.

LYMAN SEARFOSS, OF ASHLEY, PENNSYLVANIA.

TIRE-CHAIN LEVER HOOK.

Application filed February 19, 1923. Serial No. 620,036.

To all whom it may concern:

Be it known that I, LYMAN SEARFOSS, a citizen of the United States, residing at Ashley, in the county of Luzerne and State 5 of Pennsylvania, have invented a new and useful Tire-Chain Lever Hook, of which the following is a specification.

This invention aims to provide a simple but effective means whereby the flexible element of any sort, for instance the side chain 10 of an anti-skidding covering for an automobile wheel, may be tightened.

It is within the province of the disclosure to improve generally and to enhance the 15 utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention 20 shown can be made without departing from the spirit of the invention.

In the accompanying drawings:—

Figure 1 shows in side elevation, a device 25 constructed in accordance with the invention, the parts being in the positions which they will assume before the chain has been tightened; Figure 2 is an elevation showing the device as it will appear after the chain has been tightened; Figure 3 is a top plan showing the device in the position of Figure 2; Figure 4 is a cross section taken through the lever, the hook appearing in elevation.

The numeral 1 marks a connection, which 30 may be one link in a chain. The side pieces 2 of the connection 1 are provided at their ends with bearings or eyes 3. A trough-shaped lever 4 is provided, the same including a base 5 side walls 6 and a tongue 7 projecting from the base 5 and extended beyond the side walls 6, the tongue being disposed at an obtuse angle to the base. At its outer end, the tongue 7 is supplied with lateral projections 9. Those edges of the side walls 45 6 which are adjacent to the tongue 7 are

disposed at an acute angle to the tongue, as marked by the reference numeral 8. The side walls 6 of the lever 4 are provided at their corners with trunnions 10 received for rotation in the bearings 3 of the connection 1. A hook 11 is provided. The hook may be of any desired form, but, ordinarily, it is made out of a single piece of metal, bent as shown at 12 to form a two-part bill 14 and a two-part shank 15, the constituent 50 members of the bill and of the shank being in contact. The members of the shank 15 are turned outwardly to form pivot elements 16 mounted to rock in opening 17 formed in the side walls 6 of the lever 4, the shank 15 extending between the side walls 6. The numeral 18 designates a link in the chain which is to be tightened.

In practical operation, assuming that the parts are disposed as shown in Figure 1, the link 18 is engaged with the bill 14 of the hook 11. The lever 4 then is swung over into the position shown in Figure 2, the lever passing between the side pieces 2 of the connection 1, and the projections 9 of the lever resting on the side pieces. When the parts are arranged as shown in Figure 2, the pivot elements 16 are not in a straight line with the point where the projections 9 are on the connection 1 and the point where the link 18 engages the bill 14 of the hook 11, and consequently, when a pull is exerted on the chain of which the members 1 and 18 form a part, the lever 4 will not tend to swing from the position depicted in Figure 2 to the position shown in Figure 1, but will remain in the position delineated in Figure 2.

What is claimed is:—

In a device of the class described, a connection comprising side pieces provided at their ends with eyes, a trough-shaped lever including side walls and a base, the base being extended to form a tongue disposed at an obtuse angle to the base and provided at its outer end with lateral projections adapted to engage the side pieces of the connection, the side walls being provided, at those corners thereof which are diagonally opposite to the base of the tongue, with 95

2
trunnions mounted to rock in the eyes, and a hook made of a single piece of material bent upon itself to form a two-part shank and a two-part bill, the constituent members of the shank being outwardly extended to form pivot elements journaled in the side walls of the lever.

In testimony that I claim the foregoing as my own, I have hereto affixed my signature in the presence of two witnesses.

LYMAN SEARFOSS.
